UNITED STATES PATENT OFFICE.

MARTIN C. SMITH, OF PORTLAND, OREGON, ASSIGNOR OF ONE-HALF TO CHARLES R. FRAZIER, OF PORTLAND, OREGON.

VEHICLE-STORAGE BUILDING.

1,303,978.

Specification of Letters Patent. Patented May 20, 1919.

Application filed May 23, 1917. Serial No. 170,567.

To all whom it may concern:

Be it known that I, MARTIN C. SMITH, a citizen of the United States, residing at Portland, county of Multnomah, State of Oregon, have invented certain new and useful Improvements in Vehicle-Storage Buildings, of which the following is a specification.

My invention relates to the construction 10 of buildings for the storage of vehicles in general, and particularly for the storage of automobiles.

The object of my invention is to provide 15 a means for storing automobiles within the congested districts of large cities that shall conserve the valuable ground space therein, and is so illustrated in the accompanying drawings which form a part of this application for Letters Patent, and in which:—

20 Figure 1 is a diagrammatical perspective view of my device in operation.

Fig. 2 is a sectional elevation of a portion 25 of a building containing my device.

Fig. 3 is a transverse sectional elevation 30 of one of the storage chambers of my device.

Fig. 4 is a front elevation of the subject matter of Fig. 3.

Figs. 5, 6 and 7 are ground plans of 35 various arrangements of buildings to contain my device.

Like characters of reference indicate like parts through the several views of the drawings.

In general my invention consists of a plurality of elevators, each elevator having a plurality of superposed chambers therein adapted to receive a vehicle to be stored, and means whereby each elevator may be operated so as to bring any desired chamber to the main floor of the building for the purpose of receiving or discharging a vehicle.

A series of such elevators is shown in Fig. 1, indicated by 7, 8, 9 and 10, each having therein three receiving and storage chambers 11, 12 and 13.

Each elevator is operated by independent means of any convenient type, that illustrated being a hydraulic elevator motor of the vertical type, which is a preferred construction because requiring no over-head ropes or other devices to interfere with moving the vehicles over the tops of the elevators if desired.

The particular motive power is not claimed as a part of my invention, that illustrated being well known to the art, and consisting of a cylinder 14 and a plunger 15, the latter being connected direct to the elevator.

The several floors 16 of the elevator chambers may each be brought into registration with the main floor 17 of the building for the purpose of receiving or discharging a vehicle 18, as shown in Fig. 1.

Each floor 16 slopes rearwardly, as shown in Figs. 2 and 3, for the purpose of insuring that the vehicle contained therein shall always have a tendency to move toward the rear of the chamber and thus avoid the danger of the vehicle leaving the chamber at any time other than as desired when the floor of the chamber registers with the floor of the building.

Each floor 16 is also crowned transversely 75 toward the center thereof, as shown in Figs. 1 and 4, and at each edge thereof adjacent the side walls of the elevator is provided a longitudinally disposed trough 19 for the purpose of receiving the drippage of oil, water or the like, from the vehicle, and directing the flow of the same to a drainage pipe 20 at the rear of the elevator, which pipe is connected to all said troughs lying in the same vertical plane, as shown in Fig. 1.

By means of the sloping arrangement of the floors, and the troughs and pipe 20, each compartment or chamber is insured 90 from receiving any drippage from the chamber above.

Suitable guards 22 are provided for each elevator, and the building may be provided with a wash room 23 beneath the main floor 17, as shown in Figs. 1 and 2.

A pit 24 extends below the washroom 95 floor 23 sufficiently to allow the floor 16 of the upper elevator chamber to be brought into register therewith.

It is obvious that my device may be installed in many various arrangements with 100 in suitable buildings, and I have only illustrated three such arrangements.

In Fig. 5 is illustrated the plan view of a building having a central floor 17^a and a number of elevators upon each side thereof. 105

In Fig. 6 is illustrated the plan view of a

building having a floor 17^b upon one side thereof and a number of elevators upon the opposite side of the building.

In Fig. 7 is illustrated the plan of a building having a number of closely adjacent series of elevators, and a floor 17^c at one side thereof.

The arrangement shown in Fig. 7 is the most economical of ground space, and the vehicle is enabled to enter the chambers of any elevator in the rear series by passing over the flat roof or top of the elevators in front thereof.

My invention may be made of any size and of any materials deemed suitable and convenient for a device of this character, and while I have illustrated and described a form of construction and arrangement of parts found desirable in materializing my invention, I wish to include in this application for Letters Patent all mechanical equivalents and substitutes that may fairly be considered to come within the scope and purview of my invention as defined in the appended claims.

Having disclosed my invention so that others skilled in the art may be enabled to construct and to use the same, what I claim

as new and wish to secure by Letters Patent is:—

1. A storage building divided into a plurality of respectively adjacent floorless stalls, and having an inclosed pit beneath said stalls; an elevator having a plane unobstructed top thereto in each of said stalls, 35 said elevator tops coacting to form the building floor when all of said elevators are in lowered position.

2. In a storage building having a pit beneath the same, a floor formed of a plurality of vertically movable respectively adjacent platforms, said platforms coacting to form the building floor; containers integral with said platforms and normally disposed within said pit; and means to bring either of 45 said containers into alignment with said platforms.

In witness whereof I claim the foregoing as my own, I hereunto affix my signature in the presence of two subscribing witnesses, at 50 Portland, county of Multnomah, State of Oregon, this 7th day of May, 1917.

MARTIN C. SMITH.

Witnesses:

C. F. BLAKE,
CHAS. R. FRAZIER.
